STOCKING

Eric Boettcher, Southampton, Pa.

Application October 13, 1953, Serial No. 27,162

Term of patent 3½ years

(Cl. D47—7)

FIG. 1

FIG. 2

FIG. 3

Fig. 1 is a side elevational view of a stocking showing my new design,

Fig. 2 is a fragmentary front elevational view thereof, and

Fig. 3 is a fragmentary rear elevational view thereof.

The patches of shading on the leg and ankle portions indicate the continuous sheerer portions of the stocking.

I claim:

The ornamental design for a stocking, as shown and described.
